LOCK SEAL CLAMPING DEVICE

John W. Schukraft, Towson, Md., assignor to The Murray Corporation, a corporation of Maryland
Filed Oct. 10, 1961, Ser. No. 144,260
6 Claims. (Cl. 24—281)

This invention relates to a clamping device adapted to apply compressing pressure to a hose or the like of greatly varying diameter although it will be apparent that it may be applied to many other uses. It is of the type illustrated in the patent to applicant, No. 2,622,290, December 23, 1952, and it is believed to be an improvement thereon.

More specifically the clamping device of this invention includes in combination an elongated imperforate gripping member or strap having bosses in its free end to be placed over a projecting tongue on a bracket for making substantial adjustments in the length of the strap and then including on the bracket a screw which tightens the strap for a length considerably greater than the distance between the bosses on the strap and at the same time holds the strap down on the end of the strap containing the upstanding bosses to prevent any release of the strap from the bracket in the vibration of the hose or any other member to which the device has been applied.

Among the objects of the invention are to make a strap or clamping device which will allow for this adjustment of its length around the object to be clamped tightly and in substantial steps, the distance between one or more of the bosses in the strap free end.

Another object of the invention is to provide for the tightening of the strap through short distances by the fine adjustment allowed in the turning of the screw running tangential to the strap.

Another object of the invention is to a lock the strap on the projection on the bracket in any of the bosses for which the first adjustment was made in order to retain the strap in its adjusted length. If the first adjustment of the strap should leave the bend in the strap free end between the bosses, the strap will merely creep around the retaining edge of the bracket until a boss on its underside slips over the projection on the bracket edge, at which time other slipping will be prevented by the firm engagement of the inside of the boss on the projection. The hold obtained by the use of the instant invention is substantially shake proof. It is possible to use a more flexible strap because the formation of the bosses under pressure within the strap makes the strap more rigid at the location of the boss, while allowing freedom of the bending of the strap and at its bend around the bracket portion on both sides of the boss. It will be apparent that the tighter the strap is clamped by the screw, the tighter will the screw free end be pulled down on the overfolded free end of the strap and since the bosses project upwardly in this overfolded free end, it will be apparent that the block on the end of the screw around which the anchored end of the strap is wrapped rests tightly not only on the bosses, but when it should fall between them, an additional holding edge is available as they are impacted on their edges by the strap angle folded around the block at the end of the screw.

Other objects and advantages of the invention will be apparent from the following description and the accompanying drawings forming a part hereof and in which:

FIGURE 1 is a side elevational view of the strap and its bracket and screw around a hose and nipple of, for instance, an automobile radiator connection, shown in section.

FIGURE 2 is a top plan view of the clamping device.

FIGURE 3 is a top plan view of the strap with its anchoring block at one end being shown fragmentarily in section.

2

FIGURE 4 is a horizontal sectional view of the bracket base.

FIGURE 5 is a sectional view on line 5—5 of FIGURE 4.

5 FIGURE 6 is a fragmentary view of the end of the bracket showing the initial engagement of the free end of the strap therewith.

In the drawing similar numerals refer to similar parts throughout the several views. The nipple member 1 of an automobile radiator may be connected to the engine block of an automobile by the hose 2 and the connection is made tight by the clamping device of the instant invention, in which a strap 3 passes through a slot 4 in the base 5 of the bracket 6 and is anchored to the end of a screw 7 passing through a threaded opening 8 in the overfolded end of the bracket. The end of the bracket as at 9 is folded substantially parallel to the portion 10 of the base of the bracket and both parallel portions are threaded as at 11 to guide the screw longitudinally of the bracket and also to hold the free end of the screw down upon the free end of the strap. The anchored end of the strap passes around the block 12 freely rotating on the free end of bolt, where it is held by the swaged portion 13 of the bolt. The free end 14 of the strap has bosses 15 longitudinally, centrally impressed therein which project downwardly into the rubber hose being bound and serve to guide and hold the strap and bracket rigidly in place on the hose. The end 16 of the bracket has projecting centrally within the slot 4 toward the threaded end 30 of the bracket, a projection or tongue 17. This end 16 is offset slightly from the screw as shown in FIGURE 1. When the strap free end 14, containing the bosses, is wrapped around the object to be clamped and threaded into the slot 4, it is preferably pulled to the last tight position where the interior of the boss will fit substantially complementarily over the projection 17, as shown in FIGURE 6. In this position the free end of the strap is bent down around the end 16 of the bracket and then the screw 7 is tightened by the rotation of its head 18 using a screwdriver in the slot 19 to slide the block and strap anchored end over the bosses as shown in FIGURES 1 and 2. This sliding action tightly bends the strap around the end of 16 of the bracket and the tighter the pull is upon the strap, caused by the tightening of the screw, the harder the free end of the screw presses downwardly upon the bosses. It will be apparent that with the tightening of the screw, the boss on the projection 17 will be expanded, and conform to the shape of projection 17, and the bend in the strap will engage the edge of end 16 of the bracket. However, the bosses as they are engaged from their top by the anchored end of the strap and block 12, firmly hold the free end of the strap down, and the strap, portion of the anchored end of the immediately back from the block, bearing on the fold in the strap free end, around the projection 17, inhibits any creeping of the strap around this edge bracket after the interior of the boss is firmly engaged with the projection. It will also be apparent that the impression of the bosses in the strap leaves the strap whole, imperforate, so that it is not weakened substantially.

It will be apparent that many modifications of the construction shown and described in detail may be made without departing from the spirit of the invention.

What is claimed as new and is desired to be secured by Letters Patent is:

1. A clamping device comprising a strap for forming a loop about an object to be clamped, a bracket having a base substantially tangent to the object to be clamped, the base having therein adjacent one end a transverse slot the base at its end forming one boundary of the slot constituting a transverse base bar and the base having at the opposite end and extending upwardly from the base, an

end wall having a threaded opening therethrough, a screw having a forward end extending through said end wall opening across and substantially parallel to the base, the base bar at the slot end having a projection thereon, spaced from the sides of the slot and extending in the plane of the base into the slot, toward the end wall, two end portions of the strap extending upwardly through said slot, one end portion being connected to the forward end of the screw, the screw being rotatable with respect thereto, the other end portion of the strap having a series of bosses extending inwardly therealong, spaced from the sides thereof, presenting coinciding depressions upon the reverse side of the strap, the said other end of the strap being folded upon itself transversely in line with one of said bosses, with the bosses extending outwardly 15 and the strap engaging the base bar, and the depression opposite the boss at the fold receiving therein said projection, whereby as the screw is turned to move forwardly of the bracket, to tighten the clamp, the strap end on the screw will bear downwardly and slidingly against the projecting bosses on the said other end portion of the strap.

2. The clamping device of claim 1 in which the bracket end wall has a portion folded forwardly, parallel to and bearing upon the screw, to force the screw down at its forward end toward the slotted end of the base. 20

3. The clamping device of claim 1 including a block freely pivoting on the forward end of the screw the strap 25

connected to the forward end of the screw being folded around the forward face and lower edge of said block.

4. The clamping device of claim 1 in which the projection on the bracket base is rounded, with a curvature substantially complementary to the depressions within the bosses on the strap. 5

5. The clamping device of claim 1 in which the projection is placed substantially centrally of the bracket base slot and the bosses are substantially in the transverse center of the strap.

6. The clamping device of claim 1 in which the bracket end wall has a portion extended forwardly, parallel to and bearing upon the screw and the bracket base is offset adjacent its slot away from the screw and with the portions of the bracket, on both sides of the screw, being threaded and contacting the screw to firmly hold the screw in place therebetween. 10
